SPLASH GUARD FOR A BICYCLE MUD GUARD OR THE LIKE

Ruben L. Pawsat, P.O. Box 619, Maysville, Ky.

Filed Jan. 29, 1959, Ser. No. 54,384

Term of patent 14 years

(Cl. D90—5)

Fig. 1 is a front elevational view of a splash guard for a bicycle mud guard or the like showing my new design, the rear being substantially plain;

Fig. 2 is a right side elevational view thereof; and

Fig. 3 is a transverse cross-sectional view thereof taken on line 3—3 of Fig. 1.

I claim:

The ornamental design for a splash guard for a bicycle mud guard or the like, as shown and described.
